UNITED STATES PATENT OFFICE.

PRESTON R. BASSETT, OF BROOKLYN, NEW YORK, ASSIGNOR TO THE SPERRY GYRO-SCOPE COMPANY, OF BROOKLYN, NEW YORK, A CORPORATION OF NEW YORK.

MEANS FOR MAINTAINING THE FOCUS OF ARC PROJECTORS.

Application filed October 15, 1918. Serial No. 258,255.

To all whom it may concern:

Be it known that PRESTON R. BASSETT, citizen of the United States, residing at 1716 Newkirk Ave., Brooklyn, in the county of 5 Kings and State of New York, has invented certain new and useful Improvements in Means for Maintaining the Focus of Arc Projectors, of which the following is a specification.

10 This invention relates to arc lights; particularly as used in searchlights, and more specifically to a method and means for automatically maintaining the light source, which is located in the crater formed in the 15 end of the positive electrode, in a predetermined position, so as to keep the said source the proper distance from the reflector to maintain the desired projection of the light rays. In high intensity flaming arc 20 lights, for use with which my invention is particularly adapted as illustrated by the flame structure in Figures 1, 4 and 5, the source of light, instead of being in the flame of the arc, is concentrated in the crater of 25 the positive electrode, and this invention is concerned simply with positioning the light source at a definite distance from the reflector, the length of the arc being regulated by other means.

30 The most successful systems now used for this purpose comprise thermostatic devices which involve delicate and complicated mechanism requiring frequent adjustments. While some of these systems function with 35 a high degree of accuracy under favorable conditions, they are subject to inaccuracies under unfavorable conditions, such as heavy jars or shocks.

The object of this invention is to provide 40 a system whereby the position of the light source may be controlled with great accuracy under all conditions, and wherein the mechanism is simple, hardy, readily adjustable and inexpensive to manufacture.

45 Referring to the drawings wherein I have shown what I now consider to be the preferred form of my invention:

Fig. 1 is a side elevation partly in section of a searchlight lamp showing the embodiment of my invention.

Fig. 2 is a sectional side elevation of the positive electrode head.

Fig. 3 is a section taken on line 3—3, Fig. 2.

Fig. 4 is a wiring diagram.

Fig. 5 is a wiring diagram, showing a modification.

In Fig. 1 of the drawings, 1 is a fragmentary representation of a searchlight drum, below which depends a control box compartment 2 integral therewith. Within said compartment is shown the control box 3 of the lamp, from the top of which the negative and positive electrode holders 4 and 5 project upwardly into the drum. The said 50 holders may comprise standards 10 and 11, having heads 6 and 7 fixed on the tops thereof. The negative electrode 8 is shown within the head 6 and is adapted to be fed therethrough toward the positive electrode, 55 while the positive electrode 9 is shown within the head 7, and may be rotated therein and fed therethrough.

The mechanism for feeding the negative electrode through its holder may be the same 60 as that shown and described in the copending application of Elmer A. Sperry for feeding mechanism for searchlights, which on December 14, 1920, matured into Patent No. 1,362,575 and is therefore not shown 65 here; it being sufficient to state that the end 8' of the negative electrode is adapted to be automatically maintained a predetermined 70 distance from the crater in the end 9' of the positive electrode. The said end 9' on 75 the other hand, being placed along the axis of a parabolic reflector or projector 12 (see Fig. 4) should be maintained at substantially a fixed distance from said projector in 80 order to obtain the desired projection of the light rays 13. Also the positive electrode is 85 preferably rotated while the light is burning so that the end 9' will burn off evenly and a symmetric crater 14 will be formed 90 so as to confine the light source which is mostly within the crater, to as small an area 95 as possible; it being recognized that the point source is the most efficient for searchlights.

Numerous methods may be employed for 100 rotating the electrode. For this purpose I have shown the electrode 9 as gripped between two rollers 15 and 16 (Figs. 2 and 3) mounted on brackets 17 and 18 on crown gear 19 mounted for rotation on annular 105 member 20 which is integral with the head 7. One of said brackets may be hingedly mounted on the said crown gear as at 18'

and a spring 21 may be attached to projections 22 and 23 on said brackets for pressing the rollers tightly against the electrode.

5 Within the control box 3 is shown an electric motor 34 on the shaft 35 of which are provided worm teeth 36 meshing with worm gear 37 on shaft 38. On the top of shaft 38 is fixed a gear 39 adapted to turn gear 40 through an idler 41. Gear 40 is fixed on shaft 42, at the top of which, within the head 7 is also fixed bevel gear 43 meshing with the crown gear 19. Motor 34 is adapted to rotate constantly during the 10 operation of the lamp, so that the electrode will rotate continuously.

Fixed upon the same shafts 24 and 25 with rollers 15 and 16 are a pair of intermeshing gears 26 and 27. Also meshing 20 with gear 26 is a pinion 28 on the same shaft 29 with a gear 30 which in turn meshes with pinion 31. Fixed on the outer end of the same shaft 32 with pinion 31 is a star wheel 33. It will readily be seen that rotation of 25 said star wheel 33 will effect the rotation of rollers, 15 and 16 through the said chain of gears, so that the electrode 9 will be moved longitudinally.

As crown gear 19 rotates, star wheel 33 30 is obviously carried on a circular path as indicated by dotted lines 44 within the walls of head 7. Lying adjacent and below said path is shown an actuating rod 45 reaching down into the control box 3, where it is attached to a lever 46 which is pivoted at 47 on bracket 48. A magnet 49 adjacent one end of lever 46 may be employed for tilting said lever to raise rod 45. This will place the rod in the path of star wheel 33 so that 40 one of its points will engage the rod during each revolution of the crown gear 19 and cause said star wheel to revolve slightly on its own axis, and thus effect the aforementioned longitudinal movement of electrode 9. 45 A spring 50 secured to lever 46 and to an adjustable thumb screw 51 may serve to normally hold rod 45 out of the path 44 of the star wheel. Adjustments of the tension of spring 50 may be made through thumb 50 screw 51 so as to vary the strength necessary in magnet 49 to tilt lever 46.

To effect the energization of magnet 49, I desire to place the same in circuit with an additional electrode located adjacent the arc 55 for closing a circuit through said magnet when the position of the arc changes.

While such third electrode may be placed in any suitable position with respect to said arc, I have represented it at 52 below the 60 arc which is represented at 53. As shown, the electrode 52 is so positioned that as the positive electrode burns off and its end 9' recedes toward the holder 7, the lower portion or hump 54 of the arc will draw more 65 closely to the end 65 of electrode 52.

In the wiring diagram shown in Fig. 4, it will be seen that if the arc 53 touches electrode 52 a circuit will exist running from the source of power represented by a generator 55, through wires 56, 57, coil 49, wire 58 electrode 52, through arc 53 to electrode 9 and back through line 59. It is not essential, however, that the flaming portion of the arc shall actually touch electrode 52 to close said circuit, since a considerable stray 75 voltage so to speak or conducting gas normally surrounds the arc. The value of this gas as a conductor varies of course with the distance from the flame of the arc. The electrode 52 as located in the drawings is 80 constantly in engagement with the said gas, so that a weak current may always be passing through magnet 49. This current, when the end 9' of the positive electrode is in the proper place, may not be strong enough 85 to tilt lever 46, but as the arc draws closer to said electrode 52 the current will increase to a strength sufficient to tilt said lever. The tension of spring 50 may be adjusted 90 so that said tilting will take place at the desired time.

While the system of control represented in Fig. 4 has been found sufficiently sensitive to keep the light source very close to a fixed position, I have shown a slightly modified system in Fig. 5, which is adapted to respond with a greater degree of sensitivity, and which may be employed if desired. 95

In this form the current passing through electrode 52 is required to do much less work 100 than in the form shown in Fig. 4. In this form, instead of requiring said circuit to lift rod 45, it is simply required by energizing a coil 49' to trip a lever 61 to actuate contact 62, thereby closing a strong circuit through magnet 49 to effect the feeding of electrode 9. Adjustments of the strength required to tilt lever 61 may be made through adjusting screw 51' and spring 50'. One advantage of this arrangement is that, 110 since a much weaker current is required to tilt lever 61, electrode 52 may be placed a greater distance from the arc and thus be less apt to become destroyed by the intense heat. 115

Other features which are designed to aid in preserving electrode 52 from consumption or too rapid consumption by the arc or the heat from the arc, are the composition and the shape of the electrode. While it may be composed of carbon I prefer to use a metal having suitable current conducting properties, rapid heat conducting properties, and a high melting temperature. To this end I prefer to use copper which may be covered as by calorizing with aluminum or electroplating with silver or other substance capable of preventing or retarding oxidation. In shape, the electrode end 65 which is the contact making end may be 120 125 130

small enough to be confined to a small area, and may spread out to a larger body portion 65'. Thus the heat received at the end may spread rapidly away therefrom.

- 5 When consumption of the end 65 does take place, however, the tension on spring 50 or spring 50' may be lessened so that the tilting of levers 46 or 61 may still take place at the correct time to maintain the light 10 source in its proper position. Compensation for consumption of the end 65 and also adjustment of the normal position of the positive crater with respect to the projector may be made by moving electrode 52 toward the 15 arc. For this purpose said electrode is shown as mounted in a holder 66 which is slidably mounted on a bracket 67 secured to standard 11. An arm 68 on holder 66 is attached at its lower end to a rod 69 reaching 20 down into the control box 3. A spring 70 butting against a collar 71 fixed on rod 69 and against insulation 72 through which the rod passes into the control box may serve to tend to move rod 69 upwardly and thus 25 move electrode 52 toward the arc, while an adjustable nut 73 screwed upon the end 74 of rod 69 and against the lower part of insulation 72 may serve to hold said rod against the tension of said spring. Thus the turning 30 of nut 73 may serve to adjust electrode 52 with respect to the arc.

The electrical connection between electrode 52 and magnet 49 may be effected by insulating bracket 67 from standard 11 by 35 means of insulation 75, and connecting the lower end 74 of rod 69 to magnet 49 by means of conductor 76.

If it becomes desirable to feed the positive 40 electrode manually for any reason, this may be effected by the pulling of a rod 80 attached to a bell crank lever 81 pivoted at 82 on bracket 48. Said bell crank lever is normally held in inoperative position by a 45 spring 83 attached thereto and to the end of the control box 3 at 84. Upon pulling rod 80 the end 85 of bell crank lever 81 will raise lever 46 and effect the said feeding.

In accordance with the provisions of the 50 patent statutes, I have herein described the principle of operation of my invention, together with the apparatus, which I now consider to represent the best embodiment thereof, but I desire to have it understood that the apparatus shown is only illustrative 55 and that the invention can be carried out by other means. Also, while it is designed to use the various features and elements in the combination and relations described, some of these may be altered and others omitted 60 without interfering with the more general results outlined, and the invention extends to such use.

Having described my invention, what I 65 claim and desire to secure by Letters Patent is:

1. In an arc lamp, a pair of electrodes adapted to produce an arc, means for feeding one of said electrodes independently of the other, a third electrode adjacent the arc tips of said electrodes, and means controlled by the current passing through said third electrode for controlling said feeding means. 70
2. In an arc lamp, a pair of electrodes adapted to produce an arc, means for feeding one of said electrodes independently of the other, electro-magnetic means in circuit with one of said electrodes for bringing into operation said feeding means and an additional electrode adjacent the arcing ends of said first mentioned electrodes and in circuit with said electro-magnetic means, said additional electrode being adapted to engage the arc to close a circuit through said electro-magnetic means. 75

80 3. In an arc lamp, the combination with a pair of electrode holders, of mechanism for feeding an electrode thru one of said holders, means for actuating said mechanism, and an additional electrode on said holder and adjacent the arc, said additional electrode being in circuit with a source of energy and with said actuating means to energize the same in response to the position of one of the electrodes. 85

90 4. In a light projecting device, a projector, a pair of electrodes, means for positioning one of said electrodes with respect to the projector, electro-responsive means for positioning the other electrode with respect to the first electrode, and a third electrode adjacent the arc and in circuit with said first mentioned means for actuating the same. 95

100 5. In an arc light, a projector, a positive and a negative electrode adapted to produce an arc, the crater of the positive electrode containing the principal light source, an electric conductor adjacent the arcing face of the positive electrode, and means in circuit with said conductor and actuated by stray current from the arc when said electrode burns back for feeding the same forwardly to maintain said light source in a predetermined position with respect to said projector. 105

110 6. In an arc light, a positive and a negative electrode, the crater of the positive electrode containing the principal light source, means for feeding the positive electrode, an electric conductor adjacent the arc, and means in circuit with said conductor and operated by variations in the passage of current therethrough, due to variations in the electric field adjacent said conductor caused by the arc flames for controlling said feeding means. 115

120 7. In an arc light, a pair of electrodes adapted to produce an arc, means for feeding one of said electrodes, an electric conductor adjacent the arc, and means in circuit with said conductor and operated by varia- 125

130

- tions in the passage of current therethrough, due to variations in the electric field adjacent said conductor caused by the arc flames for controlling said feeding means, said conductor being so positioned relative to said electrodes and said arc that the means for controlling the feeding means is non-responsive to the burning away of one of said electrodes.
10. 8. A feeding means for electrodes of arc lights having spaced electrodes adapted to be fed toward each other comprising power driven mechanism, variable means for causing feeding of an electrode by said mechanism, and electrical means responsive to the electronic field surrounding the arc flame adjacent said electrode for governing said variable means.
9. In an arc lamp, the combination with 20 the electrode holders, of means for feeding an electrode associated therewith, separate means for feeding the other electrode and means responsive to the proximity of the arc flame for controlling one of said feeding means comprising a conductor adjacent the arc and connected to one side of the arc supply and electro-magnetic means in circuit with said conductor and said arc supply.
10. In an arc lamp, the combination with 30 the electrode holders, of means for feeding an electrode associated therewith, means responsive to the electrical properties of the arc flame for controlling said feeding means comprising a conductor adjacent the arc, electro-magnetic means in circuit therewith, 35 and a contact controlled by said electro-magnetic means and in circuit with said feeding means for controlling the latter.
11. In an arc lamp, a pair of electrodes adapted to produce an arc, means for feeding one of said electrodes, a third electrode formed of a block of copper, positioned with the greater portion thereof lying away from the arc flame, and means controlled by the relative position of said third electrode and arc for controlling said feeding means.
12. In an arc lamp, a pair of electrodes adapted to produce an arc, means for feeding one of said electrodes, a third electrode formed of a block of copper of tapering 45 shape with the thicker portions thereof lying away from the arc, and means controlled by the relative position of said third electrode and arc for controlling said feeding means.
13. In an arc light, in which the principal light source lies adjacent one electrode, an electric conductor adjacent the tip of said electrode comprising a calorized copper block, and feeding means for said electrode 50 controlled by current passing through said conductor.
- In testimony whereof I have affixed my signature.

PRESTON R. BASSETT.
